CLAIM

The ornamental design for an adjustable window grille, as shown and described.

DESCRIPTION

FIG. 1 is a perspective view of an adjustable window grille showing my new design;

FIG. 2 is a top view thereof;

FIG. 3 is a front elevatioanl view with the rear elevational view being a mirror image thereof;

FIG. 4 is a left side elevational view with the right side being a mirror image thereof; and,

FIG. 5 is a bottom view thereof.

The broken line showing a window casing and hinge that can be used to mount the adjustable window grille are for illustrative purposes only and form no part of the claimed design.

FIG. 1

FIG. 2

FIG. 3

FIG. 4

FIG. 5
